Inventor—
William M. Purvis

UNITED STATES PATENT OFFICE.

WILLIAM M. PURVIS, OF OKLAHOMA, OKLAHOMA.

RAILWAY CONSTRUCTION.

1,365,848.

Specification of Letters Patent. Patented Jan. 18, 1921.

Application filed November 16, 1920. Serial No. 424,364.

To all whom it may concern:

Be it known that I, WILLIAM M. PURVIS, a citizen of the United States, and a resident of Oklahoma city, in the county of 5 Oklahoma and State of Oklahoma, have invented certain Improvements in Railway Construction, of which the following is a specification, reference being had to the accompanying drawings.

10 The invention pertains to rail-way construction in which the rails and ties are embedded in a concrete road-bed.

It is found that in rail-way track of this construction the ties and intermediate portions of each rail remain firmly embedded 15 and in good alinement and condition, while the ends of the rails at joints soon become loose by grinding the concrete into powder under the pounding action of car trucks.

20 An object, therefore, of the invention is to provide track construction in which the meeting ends of the rails will be maintained in better alinement and working condition.

Other objects and advantages of the invention will be set forth in the ensuing 25 description.

Figure 1 of the drawings is a plan view of the improved track, with portions of the concrete dug away to expose ties and rail 30 joints.

Fig. 2 is a reproduction, on a larger scale, of a portion of Fig. 1.

Fig. 3 is a sectional view taken on the line 3—3 of Fig. 2.

35 Fig. 4 is a perspective view of a portion of the improved track, with the concrete dug away and with a section of rail broken away.

Fig. 5 is a similar view of a rail plate.

40 Fig. 6 is a similar view of a fish-bar.

Like characters of reference designate like parts in all the figures.

The track shown includes the metal ties 10, and track rails 11 which are rigidly 45 secured to said ties; the ties and rails being firmly embedded on the concrete 12.

The construction thus described is well known in the art.

In carrying out the object stated, the 50 meeting ends of the rails 11 are not secured to or supported by the metal ties 10 nor supported by any other non-yieldable material which is embedded in or supported by the concrete 12.

55 The inventor places under each joint 13 of the rails 11 a block 14 of cushion mate-

rial to support the meeting ends of said rails, said blocks being embedded in the concrete 12 and forming a yieldable connection between said rails and that portion 60 of the concrete which bears the weight of said rails and their added load.

The block 14 may be of any material which has elasticity enough to return to normal shape after yielding to shock or 65 vibration of the ends of the rails 11, for example, the block of hard wood shown in Figs. 3 and 4; the blocks being long enough to receive not only the immediate ends of the rails but also a portion adjacent said 70 ends.

In rail-way track which the inventor has constructed he has used wooden blocks 14 six inches high, eight inches wide, and two feet long; the blocks lying parallel with the 75 rails and extending an equal length under each.

These blocks 14 were obtained by sawing standard rail-ties into two-foot lengths.

There is interposed between each yieldable block 14 and its supported rail 11 a plate 15 of iron or other metal strong enough to transfer the weight of said rails over practically the entire upper surface of said block. 85

In arranging this plate 15, one of its edges, preferably its outer edge for reasons later shown, is brought integrally upward past the outer edge of the base 16 of the rail 11 as at 17 and inward over said base 90 as at 18 to where it is formed into a fish-bar 19 which is bolted flatly against the outer surface of the web 20 of the rail.

A fish-bar 21, which may be of the type heretofore used, is placed against the inner 95 surface of the web 20 of the rails 11, and bolts 22 are passed through said fish-bar and rails and through the fish-bar portion 19 of the plate 15; these bolts being provided with the usual nuts 23 which are screwed up 100 tightly to clamp the parts together.

With the plate 15 arranged in the manner described, it not only transfers the weight of the rails 11 over the blocks 14 as previously described, but also forms a strong 105 rail joint.

In further arrangement, the inner edge of the plate 15 is flanged downward along the inner side surface of the block 14, as at 24.

With the plate 15 flanged down the inner side of the block 14 in this way, and with the

block firmly embedded against outward shifting movement in the concrete 12, the lateral pounding exerted on the rails is also cushioned, keeping the rails from spreading 5 without allowing them to grind their way through the concrete.

The concrete 12 referred to commonly consists of one part Portland cement, two parts sand, and three parts crushed rock, water being added to form a plastic mixture. 10

The mixture is placed under and around the ties 10 and rails 11 and allowed to harden in the usual way.

No concrete of this kind or any other kind 15 solid and firm enough to support ties 10 and rails 11 has been found which will withstand the pounding action of a rail joint or of a metal tie or other non-yieldable support under said rail joint.

20 The intermediate portions of the rails 11, and the non-yieldable ties 10 under said portions, do, however, remain firmly embedded in the concrete 12 without being loosened by continued shock or vibration.

25 The following is claimed:—

1. In rail-way construction, ties, rails carried on said ties, the ties being embedded in concrete, the joints of the rails being supported by yieldable blocks which rest on the 30 concrete.

2. In rail-way construction, ties, rails carried on the ties, the ties being embedded in concrete, the joints of the rails being supported by yieldable blocks which are embedded in the concrete. 35

3. In rail-way construction, ties, rails carried on the ties, the ties being embedded in concrete, the joints of the rails being sup-

ported by yieldable blocks embedded in the concrete, there being a plate of non-yieldable 40 material interposed between the rails and blocks.

4. In rail-way construction, a track rail and suitable supports for intermediate portions of said rail, the end of the rail being 45 supported by a yieldable block, a depending member secured to the end of the rail and projecting downward along the side of the block.

5. In rail-way construction, track rails 50 and suitable supports for intermediate portions of said rails, the meeting ends of the rails being supported by a yieldable block, a depending member secured to the meeting ends of the rails and projecting down one 55 side of the block.

6. In rail-way construction, track rails and suitable supports for intermediate portions of said rails, the meeting ends of the rails being supported by a yieldable block, 60 a bearing plate interposed between the block and rails, said plate being secured to the rails and having a projection extending down one side of the block.

7. In rail-way construction, ties, rails carried by the ties, the ties and rails being embedded in concrete, the meeting ends of the rails being supported by a yieldable block 65 embedded in the concrete, there being a bearing plate interposed between the block and 70 rails, said plate being secured to said rails and having a projection extending down the side of the block.

Witness my hand this 27 day of October, 1920.

WILLIAM M. PURVIS.
